UNITED STATES PATENT OFFICE

117,237

DESIGN FOR A COMBINED CIGARETTE RECEPTACLE AND ASH RECEIVER

John A. Zidek, Chicago, Ill., assignor to Midland Wire & Metal Products, Chicago, Ill., a corporation of Illinois

Application August 11, 1939, Serial No. 86,618

Term of patent 3½ years

To all whom it may concern:

Be it known that I, John A. Zidek, a citizen of the United States, residing at Chicago, in the county of Cook and State of Illinois, have invented a new, original, and ornamental Design for a Combined Cigarette Receptacle and Ash Receiver, of which the following is a specification, reference being had to the accompanying drawing, forming part thereof, in which:

Fig. 1 is a side elevational view of a combined cigarette receptacle and ash receiver showing my new design;

Fig. 2 is a front elevational view thereof; and
Fig. 3 is a top plan view thereof.

I claim:

The ornamental design for a combined cigarette receptacle and ash receiver, substantially as shown.

JOHN A. ZIDEK.
